(57) **CLAIM**

The ornamental design for a fiber optic terminal cover, as shown and described.

DESCRIPTION

FIG. 1 is a perspective view of a fiber optic terminal cover showing our new design.

FIG. 2 is a top plan view.

FIG. 3 is a bottom plan view.

FIG. 4 is a left side elevation view.

FIG. 5 is a right side elevation view.

FIG. 6 is a front elevation view; and,

FIG. 7 is a back elevation view.

Any portion of the fiber optic terminal cover shown in broken lines is for the purpose of illustrating environmental structure and forms no part of the claimed design.
